(57) **CLAIM**

The ornamental design for METAL DETECTOR, as shown and described.

DESCRIPTION

FIG. 1 is a left plan view of a metal detector, showing our new design.

FIG. 2 is a front plan view of FIG. 1;

FIG. 3 is a right plan view of FIG. 1; the opposing side being a mirror image of FIG. 1;

FIG. 4 is a rear plan view of FIG. 1;

FIG. 5 is a top perspective view of FIG. 1;

FIG. 6 is a top elevational view of FIG. 1;

FIG. 7 is a bottom elevational view of FIG. 1.

The broken lines shown are included for the purposes of illustrating portions of the Metal Detector that form no part of the claimed design.
